CLAIM

The ornamental design for an automobile front fender, as shown and described.

DESCRIPTION

FIG. 1 is a side perspective view of an automobile front fender showing my new design;

FIG. 2 is a side elevation view thereof;

FIG. 3 is a partial sectional view taken along the section line 3—3 in FIG. 2; and,

FIG. 4 is a partial sectional view taken along the section line 4—4 in FIG. 2.

The broken lines shown in the drawings are for environmental illustration purposes only and form no part of the present invention.
